CAT HOUSE

Weldon R. Cook, 30700 Manzano Drive,
Malibu, Calif. 90265

Filed Feb. 9, 1970, Ser. No. 21,329

Term of patent 7 years

Int. Cl. D30—01

U.S. Cl. D30—1

FIG. 1 is a perspective view of a cat house showing my new design;

FIG. 2 is a top plan view thereof;

FIG. 3 is a side elevational view showing one of the sides hidden in the view of FIG. 1; and

FIG. 4 is a side elevational view showing the other side hidden in the view of FIG. 1.

I claim:

The ornamental design for a cat house, substantially as shown.
